(57) **CLAIM**

We claim the ornamental design for a touch computer, as shown and described.

DESCRIPTION

FIG. 1 is a front perspective view of a touch computer according to a first embodiment of the present invention;
FIG. 2 is a front view thereof;
FIG. 3 is a top view thereof;
FIG. 4 is a rear view thereof;
FIG. 5 is a rear perspective view thereof;
FIG. 6 is a left side view thereof;
FIG. 7 is a right side view thereof;
FIG. 8 is a right side view thereof, with the monitor portion swiveled in a forward tilted position;
FIG. 9 is a right side view thereof, with the monitor portion swiveled in a backward tilted position;
FIG. 10 is a right side view of a touch computer, according to a second embodiment of the present invention, shown as wall-mounted; and,
FIG. 11 is a front perspective view of a touch computer (with a base portion as shown in the first embodiment removed) thereof.
